US0D1094019S

(12) United States Design Patent (10) Patent No.: US D1,094,019 S
(45) Date of Patent: * Sep. 23, 2025

(54) BOWL

(71) Applicant: YETI Coolers, LLC, Austin, TX (US)

(72) Inventors: Kyle Ellison, Austin, TX (US); Dustin Bullock, Austin, TX (US); Colin Darling, Austin, TX (US)

(73) Assignee: YETI Coolers, LLC, Austin, TX (US)

() Term: 15 Years

(21) Appl. No.: 29/808,543

(22) Filed: Sep. 21, 2021

Related U.S. Application Data

(63) Continuation of application No. 29/769,351, filed on Feb. 4, 2021, now Pat. No. Des. 933,427, which is a continuation of application No. 29/716,327, filed on Dec. 9, 2019, now Pat. No. Des. 911,780, which is a continuation of application No. 29/658,677, filed on Aug. 1, 2018, now Pat. No. Des. 869,241.

(57) CLAIM

The ornamental design for a bowl as shown and described.

DESCRIPTION

FIG. 1 is a top, front, right perspective view of a bowl showing our new design;

FIG. 2 is a front view thereof, wherein the rear view is a mirror image of FIG. 2;

FIG. 3 is a right side view thereof, wherein the left side view is a mirror image of FIG. 3;

FIG. 4 is a top view thereof;

FIG. 5 is a bottom view thereof; and,

FIG. 6 is a cross-sectional view at 6-6 in FIG. 4 thereof. The broken lines depict features of the bowl that form no part of the claimed design.

1 Claim, 6 Drawing Sheets
